No. 819,351.

PATENTED MAY 1, 1906.

H. F. KELLEY.

THREAD PARTING MECHANISM FOR LOOMS.

APPLICATION FILED SEPT. 15, 1905.

UNITED STATES PATENT OFFICE.

HERBERT F. KELLEY, OF LEWISTON, MAINE, ASSIGNOR TO DRAPER COMPANY, OF HOPEDALE, MASSACHUSETTS, A CORPORATION OF MAINE.

THREAD-PARTING MECHANISM FOR LOOMS.

No. 818,351.

Specification of Letters Patent.

Patented May 1, 1906.

Application filed September 15, 1905. Serial No. 278,538.

To all whom it may concern:

Be it known that I, HERBERT F. KELLEY, a citizen of the United States, and a resident of Lewiston, county of Androscoggin, State of Maine, have invented an Improvement in Thread-Parting Mechanism for Looms, of which the following description, in connection with the accompanying drawings, is a specification, like characters on the drawings representing like parts.

This invention relates more particularly to so-called "feeler-looms" provided with automatic mechanism for replenishing the running filling prior to complete exhaustion thereof.

In such looms the end of the old filling extends from the cloth to the shuttle containing the filling-supply to be abandoned at the time filling change is to be effected.

Means have been devised to part or sever such thread adjacent the shuttle and thereafter to part it adjacent the edge of the cloth, and in United States Patent to Draper, No. 683,423, dated September 24, 1901, mechanism is shown for not only so parting the thread, but also to catch or hold the severed piece and prevent it from being woven into the cloth.

The parting adjacent the cloth is effected by a thread-cutting temple, and the thread is clamped and parted adjacent the shuttle by separate mechanism, after which the latter is moved toward the cloth to slightly slacken the clamped end of thread as it is brought into range of the thread-cutting temple to avoid breaking the thread.

My present invention is in some of its general features very similar to the structure shown and described in the patent referred to; but I have devised improved means for more securely and effectually clamping the thread, so that there can be no tendency for it to pull out from the clamp prematurely, and thereby I insure the parting by the temple thread-cutter and prevent any liability of the filling end being woven into the selvage of the cloth.

The novel features of my invention will be fully described in the subjoined specification and particularly pointed out in the following 50 claims.

I have shown my invention as applied to a loom wherein the running-shuttle is provided

automatically with a fresh supply of filling at the proper time; but it will be manifest that it is equally applicable to a loom provided with shuttle-changing mechanism.

Figure 1 is a transverse sectional view of a portion of a loom provided with automatic filling-replenishing mechanism, showing a portion of such mechanism, one embodiment of my invention being illustrated in connection therewith and in normal inoperative position. Fig. 2 is a top plan view of a portion of the mechanism shown in Fig. 1 confined principally to the parting and clamping devices. Fig. 3 is an inner side view, enlarged, of the thread-parter and thread-clamp after the thread has been clamped and parted. Fig. 4 is a top plan view thereof; and Fig. 5 is a transverse section on the line 5-5, Fig. 3, looking toward the right and showing clearly the manner in which the thread is clamped.

As in the patent referred to, the parter and clamp are herein shown so constructed and arranged that they will be in position to act upon the filling when the shuttle is properly boxed, the shuttle-feeler forming a support for the parter and clamp, the thread-catcher being mounted separately and being stationary as a whole.

Referring to Fig. 1, the lay A³, the feeder F to hold the filling supplies or carriers b, the transerrer f', fulcrumed at f, the controlling rock-shaft d', turned in the direction of arrow 50 when the replenishing mechanism is 85 to be operated, the notched dog m^x, operatively connected with the depending end of the transerrer, and the bunter C² on the lay to at times coöperate with the dog may be and are all as in said patent. So, too, the 90 shuttle-feeler Y, having its hub y, Fig. 2, mounted on the stud a to rock thereon and also to move laterally thereon, (the means to effect such lateral movement forming no part of my invention,) the stud y² on the shuttle-feeler Y, having an attached finger n' to control the rotative movement of the dog m^x on its support, the arm d¹², fast on rock-shaft d' and bearing on the pin 30 on the feeler Y, and the spring S^x, Fig. 1, attached at one end 100 to the arm and fixed at its other end to normally maintain the shuttle-feeler and the parts carried thereby, and the dog m^x in normal inoperative position, as illustrated in

Fig. 1, may be and are as in the patent hereinbefore referred to.

The upper extremity of the feeler Y is notched at 1, Figs. 1 and 3, to receive the filling-thread when the feeler is moved into operative position adjacent the mouth of the replenishing shuttle-box B^x, Fig. 1, and a fixed cutting-blade 2 is secured to the feeler at the lower edge of the notch 1.

10 On the headed screw-stud 3 as a fulcrum is mounted the member 4, which is at once a cutting-blade and a clamping-jaw, its lower edge 5 coöperating with the blade 2 to part the filling-thread at the proper time, (see Fig. 15,) said member 4 resting against the flat face of the feeler and having at its front end a depending heel 6, Fig. 3.

A fixed or stationary member 7 of the thread-clamp is arranged to coöperate with 20 the adjacent face of the combined blade and clamp member or jaw 4, the member 7 having a notched end 8 adjacent the feeler-notch 1, but with its lower edge 9 above the upper edge of the fixed blade 2. This fixed member 7 is held in place by the screw-stud 3 and by a pin 10, fixed in the feeler and passed through the member 7, the pin extending loosely through a slot 11 in the movable member 4. (See dotted lines Fig. 3.)

30 By reference to Fig. 4 it will be seen that the member 4 is cut away or reduced in thickness at 12 to accommodate the fixed member or jaw 7 of the thread-clamp. Adjacent the outer face of the member 7 I have provided a 35 second clamping member 13, fulcrumed on the screw-stud 3 and fixedly attached, as by rivets 14, to the thick forward end of the member 4 to move in unison therewith and so placed that it moves up and down against the contiguous face of the fixed clamping-jaw 7. The member 13 is also slotted to correspond with the slot 11 for the pin 10, and in Figs. 4 and 5 the relative positions of the members 4, 7, and 13 are clearly shown. A spring-washer 45 15, interposed between the head of the screw-stud 3 and the adjacent face of the member 13 of the thread-clamp, holds the said member 13 yieldingly pressed against the fixed jaw 7 and presses the latter against the blade-jaw 4, in turn holding the latter against the inner face of the feeler. A thread-parter comprising the fixed blade 2 and the movable blade 4, is thus provided with a double-acting thread-clamp comprising the movable jaws 4 and 13 50 and the interposed fixed jaw 7, both parter and clamp being mounted on the shuttle-feeler, the member 4 being common to both parter and clamp and constituting a blade-jaw.

When the parter and clamp are in position to act upon the filling-thread, as will be the case when the lay has completed its forward movement, then the filling-thread will enter the feeler-notch 1 and the notch 8 of the stationary clamp-jaw 7, the blade-jaw 4 and jaw 13 then being open. Thereafter

when the members 4 and 13 are closed they first act upon the thread t, Fig. 5, pressing it down over the lower edge 9 of the notch 8 and at each side of the jaw 7, clamping it tightly between the faces thereof and the adjacent faces of members 4 and 13, and as the said members continue to descend after the thread has been so clamped its edge 5 will coöperate with the fixed cutting-blade 2, parting the thread.

In Fig. 5 the thread t is shown as clamped and also severed or parted. By the double-acting clamp thus described the thread is held tightly with absolute certainty, with no opportunity for it to slip or draw through the 80 clamping members, insuring its movement into the field of action of the thread-cutting temple T, Fig. 2, when the feeler Y returns to normal position.

The setting or opening of the parting and 85 clamping devices is effected by coöperation of the pin 16 with a part of the thread-catcher C, substantially as in the patent to which I have previously referred, and as such operation is fully described therein it needs no explanation herein.

When the clamp and parter are bodily moved into operative position, the blade-jaw 4 and jaw 13 are open and the heel 6 is in the path of a portion of the lay to be struck as the 95 lay completes its forward beat to thereby rock the blade-jaw and jaw 13 on their fulcrum 3 from the relative position shown in Fig. 1 to that shown in Fig. 4, successively clamping and parting the thread t adjacent 100 the shuttle.

The lay is shown in Fig. 1 as cut away (see dotted lines) to leave a shoulder 17 in the path of and to act upon the heel 6 to close the movable members of the parter and clamp at 105 the proper time.

As the return movement of the shuttle-feeler Y takes place the parted and still clamped thread is brought into engagement with the thread-catcher C before the clamp is 110 opened, so that when the temple thread-cutter operates to part the thread adjacent the cloth the severed piece of thread will be held by the thread-catcher in a well-known manner.

Rocking of the shaft d' in the direction of arrow 50, Fig. 1, positions the dog m^x in the path of the bunter C^x and also permits the operative positioning of the shuttle-feeler, so that if the shuttle is properly boxed the 120 thread-parter and thread-clamp will be positioned to act upon the thread, as has been described.

If the shuttle is improperly boxed, the feeler will not move far enough to bring the 125 parter and clamp into operative position, and as the filling-replenishing mechanism will not operate at such time the described operation of the thread clamp and parter will not be effected.

Having fully described my invention, what I claim as new, and desire to secure by Letters Patent, is—

1. In an automatic filling-replenishing loom, a thread-parter and a thread-clamp, each comprising a movable and a relatively fixed member, to act upon the thread of the filling-supply to be abandoned, the fixed member of the clamp coöperating with both movable members to securely clamp the thread, and means to actuate the movable members to successively clamp and part the thread upon replenishment of filling.
2. In an automatic filling-replenishing loom, a thread-parter and a thread-clamp, each comprising a movable and a relatively fixed member, to act upon the thread of the filling-supply to be abandoned, the fixed member of the clamp coöperating with both movable members to securely clamp the thread, a connection between the movable members, and means acting through such connection to operate the movable members in unison to successively clamp and part the thread upon filling-replenishment.
3. In an automatic filling-replenishing loom, a thread-parter and a thread-clamp, each comprising a movable and a relatively fixed member, bodily movable upon replenishment of filling into position to act upon the thread of the filling-supply to be abandoned, the fixed member of the clamp being interposed between the said two movable members and coöperating therewith to clamp the thread, and means to actuate the movable members in unison to clamp and part the thread upon replenishment of filling.
4. In an automatic filling-replenishing loom, a thread-parter and a thread-clamp, arranged in juxtaposition and adapted to act upon the thread of the filling-supply to be abandoned, a movable combined parting-blade and clamp member, forming one element of the parter and clamp, a second clamp member movable with said first-named member, means to operatively move said members upon replenishment of filling, and a relatively fixed member of the clamp, with which both movable members coöperate to doubly clamp the thread.
5. In an automatic filling-replenishing loom, a thread-parter and a thread-clamp, arranged in juxtaposition and adapted to act

upon the thread of the filling-supply to be abandoned, the parter including a fixed blade and the clamp a fixed member, a movable combined parting-blade and clamp member movable between and adapted to co-operate with both of said fixed members, a second movable clamping member coöperating with the fixed member of the clamp and connected with the combined parting-blade and clamp member, and means to move the latter and the second clamping member in unison, to clamp the thread at each side of the fixed member of the clamp and then part the thread.

6. In an automatic filling-replenishing loom, a thread-parter and a thread-clamp, bodily movable upon replenishment of filling into position to act upon the thread of the filling-supply to be abandoned, the parter including a fixed blade and the clamp including a parallel fixed jaw, a combined blade and jaw movable between said fixed members and coöperating with each, a jaw fixedly connected with the combined blade and jaw and coöperating with the outer face of the fixed jaw of the clamp, and means to yieldingly press the fixed and movable members laterally against each other when actuated upon replenishment of filling, and means to effect actuation of the movable members in unison.

7. In an automatic filling-replenishing loom, a shuttle to contain a supply of filling, a shuttle-feeler, movable into operative position prior to filling change, means mounted on the feeler to act upon the thread of the filling-supply to be abandoned, said means including a fixed blade and a fixed jaw, two connected, movable members one of which coöperates only with the said jaw and the other with both the jaw and the fixed blade, whereby the thread is doubly clamped before it is parted, and means to operate the movable members to clamp and then part the thread when the shuttle-feeler is operatively positioned.

In testimony whereof I have signed my name to this specification in the presence of two subscribing witnesses.

HERBERT F. KELLEY.
